(57) **CLAIM**

We claim the ornamental design for a the rear trigger water misting fan, as shown and described.

DESCRIPTION

FIG. 1 is a top perspective view taken from the right front corner of the rear trigger water misting fan showing our new design;

FIG. 2 is a rear bottom perspective view of the rear trigger water misting fan;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom view thereof.

The broken lines in the drawings depict environmental subject matter only and form no part of the claimed design.
